8873

UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 14,458, dated November 27, 1883.

Application filed September 26, 1883. Term of patent 3½ years.

To all whom it may concern:

Be it known that I, MARY TURNER, of the city, county, and State of New York, have invented and produced a new and original Design for a Pattern of a Girl's Costume, (numbered 8,873); and I do hereby declare that the engraved prints accompanying this specification convey to any one accustomed to using paper patterns a clear understanding of how a garment made up by the pattern will appear.

The design shows a walking-skirt with an overdress, which latter has sack-fronts that are shown rolled back in long narrow lapels at the top, exposing a narrow vest, and are

shown below the lapels in *revers*, and a half-fitted back that is pointed at the center, and exhibits under-folded plaits in its skirt portion. Coat-sleeves and a rolling collar are added.

What I claim as my invention, and desire to secure by Letters Patent, is—

The design for a girl's costume, as shown in the engraved prints accompanying this specification.

MARY TURNER.

Witnesses:

ALFRED FRANCIS,

MARCELLUS CARLETON SHATTUCK.
